UNITED STATES PATENT OFFICE.

WILHELM BRÄUNING, OF BERLIN, GERMANY, ASSIGNOR TO DEUTSCHE WERKE AKTIENGESELLSCHAFT, OF BERLIN, GERMANY, A CORPORATION OF GERMANY.

FIREARM.

1,401,579.

Specification of Letters Patent. Patented Dec. 27, 1921.

Application filed April 30, 1921. Serial No. 465,920.

To all whom it may concern:

Be it known that I, WILHELM BRÄUNING, a citizen of the German Republic, residing at Berlin, Germany, have invented new and 5 useful Improvements in Firearms, (for which I have filed application in Germany Sept. 28, 1919,) of which the following is a specification.

This invention relates to the Brauning fire-arm and is of that type in which the breech-lock turns upward and carries the firing-lock with rearwardly projecting hammer or striker. The invention as compared with this existing type of fire-arm, consists 10 in that on the countersunk or set-back breech and lock-carrying bar there is secured an angle-piece which with its horizontal end extends to the breech-locking frame and has a furcated upright portion to serve as a 15 guide for the striker. This furcation consists in a bore for the passage of the rear thick portion of the striker and of an upwardly extending slot to suit the adjacent thinner portion of the striker; said slot ending 20 rearwardly in an enlarged recess forming a rest for the retention of the striker in its safety position. As a further improvement in accordance with this invention, the extractor is slidably mounted in the 25 set-back of the breech-bar and is kept, from dislodging, by the superposed barrel-breech.

An embodiment of the invention is shown in the accompanying drawings, in which:

Figure 1 is a side view of the breech part 30 with longitudinal section of the stock and showing the striker cocked and in safety position.

Fig. 2 is a corresponding plan.

Fig. 3 is a side view with the stock re- 40 moved and the arm in its after-firing position.

Fig. 4 is a side view like Fig. 3 but showing the open breech.

Figs. 5 to 7 are perspective views of de- 45 tails hereinafter described.

As clearly shown in the Figs. 1 and 2, the breech-lock *k* is made in the form of a frame of flat bar-iron in which is fixed the breech-block *i* and the therethrough project- 50 ing striker *b* with its spring *f*. The frame *k* is hinged or pivoted to the breech-end *h* of the barrel *l*, said breech-end being firmly fixed to the breech-supporting bar *s*. The barrel-breech *h* is made of sharp-angled 55 metal. The bar *s*, made of flat metal, car-

ries a fixed angle-piece *w* of flat metal having an aperture *w*¹ for guiding the rear thick portion *b*¹ of the striker *b*. For cocking the striker the head *b*² of same is pulled to the rear, when the percussion pin at the front end will be retained in cocked position by the usual catch *u*¹ of the detent *u*, see Fig. 3. The catch *u*¹ is made by slitting the end of the detent *u* and then turning up the middle portion. The projecting fork like portions *u*² are shaped to form bearings for cradling the lateral lugs *z*² of the trigger *z*. The trigger is provided with a tip *z*¹ which bears against the detent and supports same in its idle position as in Figs. 70 1 and 4. The trigger *z* is entirely made of flat metal in a stamping and bending or shaping operation. The aperture *w*¹ of the angle-piece *w* communicates upward with an open slot of a width corresponding to the 75 striker-portion forward of *b*¹ thereof, so that in cocking the striker its thinner portion passes up the slot and allows the breech to be opened, see Fig. 4. Above the aperture *w*¹ at the rear of the slot is formed a recess 80 *w*² into which the part *b*¹ of the striker engages after cocking. The fire-arm is then cocked in safety position, see Figs. 1 and 2. By extending the horizontal forward end of the angle-piece *w* to contact with the breech- 85 frame *k* the latter is locked from the rear, while upward turning of same is prevented by the engagement of the striker-portion *b*¹ in the aperture *w*¹ of the angle-piece *w*, see Fig. 3. 90

The extractor *x* consists of the base plate *x*¹ and the extractor-claw *x*², the whole being made of flat metal by stamping and bending. The extractor is shiftingly carried in the set-back *s*¹ of the bar *s* and is held above by 95 the breech *h* of the barrel. Movement is imparted to the extractor, at opening and closing of the breech, in causing a suitably shaped forward end or nose of the breech-frame to engage in side slots formed in the 100 base plate *x*¹ of the extractor. All locking parts together with the lock and the barrel are carried by the supporting bar *s* to which they are suitably fixed as and where required. 105

I claim:

1. Breech-mechanism for fire-arms which consists in a barrel with a connected square-shaped breech-piece, an upwardly swinging breech-locking device, a striker mounted 110

endwise in said device and projecting rearwardly therefrom, a breech-supporting bar, an offset in said bar, an angle-piece fast on same and extending to the rear of said locking device, said angle-piece having an aperture for guiding said striker.

2. Breech-mechanism for fire-arms consisting in a barrel with a breech-piece, an upwardly swinging locking frame for same, 10 a striker mounted endwise in the frame, and projecting rearwardly therefrom, a breech-supporting bar, an angular guide-piece fast on the bar, said guide-piece being apertured, slotted and recessed at the rear of the slot 15 to accommodate the striker in its different operative positions, a catch for the striker, a trigger operatively connected with the

catch, and an extractor for removing empty cartridges from the barrel.

3. Breech-mechanism for fire-arms consisting in a barrel with a square-shaped breech-piece, an upwardly swinging breech-locking frame hinged to the breech-piece, a striker mounted in said frame to project endwise therefrom, an offset breech-supporting frame, means for locking and releasing said frame, a shiftable extractor bedded in the offset and covered by the breech of the barrel, projecting lugs on the extractor, a nose-piece connected with said frame for the engagement with said lugs in operating said extractor, and means for retaining the striker at safety and for firing the arm.

WILHELM BRÄUNING.
